COMBINATION LEG AND CATCH
FOR DAVENPORTS

Irvin C. Poskin, Los Angeles, Calif.

Application June 23, 1945, Serial No. 601,262

9 Claims. (Cl. 5—38)

1

The present invention relates to improvements in bed davenport.

More specifically, the invention relates to a combination leg and catch means for supporting the back of the davenport while in an extended position and for latching it in its upswung position.

In my copending application Serial Number 560,607, filed October 27, 1944, now Patent No. 2,438,127 granted March 23, 1948, I disclose a separately constructed yet cooperatively arranged supporting leg and catch for said leg.

It is one of the more important objects of the present invention to combine these separate parts to function as a single unit, either as a leg or as a catch. In this respect it is a further object to simplify and reduce the number of parts and cost of manufacture by utilizing a single piece of mechanism where formerly it required the use of two.

A further object is to provide more positive means both for maintaining the leg in its adjusted position while supporting the back of the davenport in an extended position and for maintaining the back upright when the davenport is utilized as a seat. The latter means is supplied by the use of a prong forming a part of the leg which prong engages an eye-bolt secured in the arm rest of the davenport.

Other objects, advantages and features of invention will hereinafter appear.

Referring to the accompanying drawing which illustrates what is at present deemed to be a preferred embodiment of the invention,

Fig. 1 is a fragmentary perspective view of a corner portion of a davenport showing the invention applied thereto, a portion of the upholstery being removed adjacent the applied device.

Fig. 2 is an enlarged fragmentary horizontal sectional view taken on line 2—2 of Fig. 1, some portions of the structure being shown in plan.

Fig. 3 is a fragmentary elevational view looking in the direction of the pointing arrow 3 found in the lower left hand part of Fig. 2.

Fig. 4 is a fragmentary elevational view showing the catch functioning as a leg when supporting the back in an extended position.

Fig. 5 is a detail perspective view of the pivot means for adjustably supporting the combined leg and catch.

Fig. 6 is a perspective view of the complete davenport showing the improved leg and catch functioning in full and dotted line positions.

2

Fig. 7 is an end elevation of the davenport functioning as a bed.

Referring in detail to the drawing, 6 indicates the back of the davenport and 7 the arm rest thereof. Into each end portion of said arm rest is screwed an eye-bolt 8 provided with the eye-opening 8a and horizontally spaced from said eye-bolt into the up-swung davenport back is secured a circular bracket 9 for adjustably supporting the combined leg and catch 10, said bracket being provided with a central annular recess 11 in one face thereof and an axial opening 12 of lesser size than said recess and communicating therewith in the face of said bracket which is opposite said recess thereby providing an annular shoulder 13 adjacent the opening 12. Cooperatively joined to the bracket 9 by means of screws 14 screwed into the back of the davenport is a circular plate 15 provided with a central recess or depression 16. 20 A circular bearing 17 has a circumferential flange 18 rotatively mounted with a working fit in the recess 11 between the inner face of the plate 15 and the shoulder 13, there being an axial bore 19 through the flanged end of said bearing which axially alines with the recess 16 and forms a continuation thereof. Said bore 19 is preferably of a length equal to the combined lengths of the recess 11 and opening 12.

The circular body portion of the bearing 17 extends loosely through and projects beyond the outer face of the bracket 9, there being a deep transverse slot 20 extending all the way diametrically across the projecting portion of the bearing 17 as fully shown in Fig. 5 dividing it into an upper segment 21 and a lower segment 22.

Diametrically opposite holes 23 and 24 provide for the mounting of a pin 25 between the arms formed by said upper and lower segments, said pin bisecting the produced axis of the bracket 17 40 at a right angle to said segments at a point midway of their length.

Said pin 25 cooperates with an elongated slot 26 in the combined leg and catch 10, said combined leg and catch being also pivoted to swing 45 about the pin 25 through the desired angle in the slot 26, whereby its catch prong 28 may be fed into the opening 8a and when so engaged maintain the davenport back 6 in the upright or upswung position as shown in Fig. 1. In order to provide for the latter operation the combined leg and catch together with the bearing 17 are rotated in an anti-clockwise fashion in a plane parallel to the back of the davenport sufficiently

far to permit the point of the prong to enter the eye **8a** and then the parts are given a clockwise turn until the operation of seating the prong securely in the eye is completed.

When it is desired to use the combined leg and catch as a leg the prong **28** is detached from the eye **8a** by an anti-clockwise movement and the back **6** is permitted to lower to a point adjacent the floor **29** as shown in Fig. 4, during which movement the leg **30** is manually swung to a perpendicular position with the back and the end of the leg adjacent the slot **26** is projected into the bore **19** until the inner end of the leg seats in the depression **16**, the elongated slot **26** providing for this telescopic seating of the pivoted end of the leg, the frictional contact of the leg in the bore sufficing to maintain the leg thus positioned without endangering it dropping by gravity while the back is further lowered to the point wherein the foot **31** of the leg rests upon the floor **29** in a temporary locked condition.

When it is desired to adjust the back to its upright position and lock it so, the back is elevated sufficiently far to withdraw the leg from its telescopic relation with the bore **19** and recess **16** and at the completion of the up-swung movement the leg is rotated in a clockwise direction during which movement the prong is simultaneously fed into the eye opening **8a**.

It will be seen that the eye-bolt **8**, functions as a latch element, with which the leg's laterally extending catch arm or prong **28** co-operates. This swingable leg consists of a single straight run and said prong is spaced a considerable distance from the attached end of the leg, being located between the free end of the leg and the axis about which it swings. These co-operating catch and latch elements may be varied as to their details, without departing from the scope of the claimed invention, provided they are related to the leg and back of the davenport in the manner which has been described.

It should be understood that the present disclosure is for the purpose of illustration only and that this invention includes all modifications and equivalents which fall within the scope of the subject matter claimed.

What I claim is:

1. In a davenport having a swingable back and an upstanding arm rest at each end of said back, a bearing member carried by an end portion of said back and having a socket directed into the back in relation to the rear surface thereof, a leg slidably pivoted to said bearing member and thereby rendered adjustable between two positions in one of which it can have its attached end portion projected into said socket so that it is usable to support said back from the floor in a downswung position and in the other of which position it overlies the adjacent end portion of the arm rest at that end of the structure, latching means whereby said leg in the latter position is connected with the adjacent arm rest to prevent the down-swinging of the back, said latching means comprising a prong on said leg which projects laterally therefrom in a spaced relation to the ends of the leg, and an eye-bolt, carried by said arm rest to receive said prong.

2. In a davenport, a frame including laterally spaced arm rests, a back hinged to said frame and swingable upwardly within said arm rests and rearwardly to horizontal position, an eye-bolt secured to the inner end portion of each of said arm rests, a bracket secured to each end portion of said back, a bearing rotatively mounted in each

said bracket, a leg for each of said brackets including a foot, pivoting means securing said leg to said bearing for both lateral and longitudinal movement in relation thereto, said bearing being

5 provided with a slot to accommodate said lateral movement and with a bore to accommodate said longitudinal movement, and a catch carried by each said leg engageable in the eye of the adjacent eye-bolt to maintain the back upright when

10 the davenport is to be used as a seat.

3. The subject matter of claim 2 and, means to rotatively mount said bearing in said bracket, said means comprising a flange surrounding said bearing adjustably mounted in a recess in said bracket, and a plate provided with a depression and joined to said bracket in such a manner that said depression forms a continuation of said bore.

4. In a davenport having a back swingable from a horizontal to an upstanding position and vice versa and an upstanding arm rest at each end of said back, a bearing member carried by an end portion of said back and having a socket directed into the back in relation to the rear surface thereof, a leg having a longitudinal slot through 25 one of its end portions, a pin carried by said bearing member and having a working fit in said slot so that said leg is thereby rendered adjustable between two positions in one of which it can have its attached end portion projected axially into 30 said socket so that it is usable to support said back from the floor in a downswung position and in the other of which positions it overlies the adjacent end portion of the arm rest at that end of the structure, and latching means comprising two 35 cooperating members, one carried by said leg and the other by said arm rest whereby said leg in the latter position is connected with the adjacent arm rest to prevent the down-swinging of the back.

40 5. In a davenport, a frame including laterally spaced apart arm rests, a back hinged to said frame and swingable between said arm rests from a horizontal to an upright position and vice versa, a bracket secured to each end portion of said back, a bearing rotatively mounted in each said bracket, a leg for each of said brackets, and pivoting means securing said leg to said bearing for both lateral and longitudinal movement in relation thereto, said bearing being provided with a slot to accommodate said lateral movement and with a bore to accommodate said longitudinal movement.

6. The subject matter of claim 5 and, a latching member secured to the inner end portion of each 55 of said arm rests, and means carried by each said leg and operatively connectable with said member to maintain said back upright when the davenport is used as a seat.

60 7. The subject matter of claim 5 and, a plate member carried by said back rearward of said bracket, said plate member having a socket directed into said back in relation to the rear surface thereof, said socket axially alining with said bore.

65 8. The subject matter of claim 5 and, a plate member carried by said back rearward of said bracket, said plate member having a socket directed into said back in relation to the rear surface thereof, said socket axially alining with said bore, each said leg in its laterally adjusted position overlying the adjacent end portion of the arm rest at that end of the structure, and latching means carried by each said arm rest whereby 70 said leg in the latter position is connected with 75

the adjacent arm rest to prevent the down-swinging of said back.

9. The subject matter of claim 5 and, means for rotatively mounting said bearing in said brackets, said means comprising a flange surrounding the bearing and adjustably mounted in a recess in the bracket, a plate provided with a depression and joined to each said bracket in such a manner that said depression forms a continuation of said bore, each said leg in its laterally adjusted position overlying the adjacent end portion of the arm rest at that end of the structure, and latching means carried by each said arm rest whereby said leg in the latter position is connected with the adjacent arm rest to prevent the downswinging of said back.
